UNITED STATES PATENT OFFICE.

GEORGE HAMILTON-GRAPES, OF MELBOURNE, VICTORIA, AUSTRALIA.

INTERNAL-COMBUSTION ENGINE RELATING TO THE CARBURATION OF HYDROCARBON-LIQUID FUEL.

Application filed August 20, 1923. Serial No. 658,455.

To all whom it may concern:

Be it known that I, GEORGE HAMILTON-GRAPES, a subject of the King of Great Britain, residing at Melbourne, in the State of Victoria, Commonwealth of Australia, have invented certain new and useful Improvements in Internal-Combustion Engines Relating to the Carburation of Hydrocarbon-Liquid Fuel, of which the following is a

specification.

The present invention refers to internal combustion engines and specifically to the carburation of hydrocarbon liquid to be employed as the fuel agent in the engine cylinders and in which vaporization of the moist particles resident in the carburetted mixture effected by any usual form of carburetting device is effected in a retort so arranged relative to the mixture stream that said particles are trapped therein and vaporized by the heat from the engine exhaust gases.

An example of such a retort is illustrated in the complete specification of Patent No. 1,471,599 dated October 23, 1923, in which the exhaust gases are by-passed from the engine exhaust manifold to a jacket surrounding said retort which arrangement results in the latter being located at an appreciable distance from and below the maximum heat position in the exhaust manifold.

According to the present invention the maximum heat position is secured for the retort by a construction of the engine exhaust manifold so that the retort may be directly fitted therein and also a valve which latter is preferably thermostatically governed and controls the supply of exhaust gases about the retort.

A practical form of the invention is depicted in the accompanying drawings in which

Fig. 1 is a central horizontal section through an engine exhaust manifold showing the end chamber construction with a retort fitted in position therein in accordance with this invention.

Fig. 2 is an end elevation of the retort, and the conductor associated therewith viewed from the delivery end of the latter.

Fig. 3 is a plan of the end of exhaust manifold which is chambered to receive said retort and

Fig. 4 is a side elevation, partly in section, of the same.

The engine exhaust manifold 5 is a straight tube and at the engine end cylinder position 6 terminates in an enlargement forming a chamber 7 to receive the retort chamber 8 secured to said chamber 7 by lugs 7^a and flange 10^a joined by screws as at 9 said retort being offset from the passage 10 the wall of which latter is integral with the retort 8. The inlet 11 of the passage 10 communicates with the delivery from any ordinary carburetter, and said inlet, passage and retort are constructed to function in accordance with applicant's beforementioned Letters Patent. To facilitate an understanding of the stream line of the carburetted mixture and the manner in which same throws out moist particles into the retort chamber 8 the stream line is shown in said passage 10 the line being approximately correct having been ascertained from an experimental construction made of glass.

Directly opposite the mouth 12 of the retort 8 an annulus 13 is formed in the wall of the passage 10 into which moist particles may collect and feed downwardly into said mouth (see Fig. 1).

The delivery end of said passage 10 terminates in a flange 14 which is used to connect same to the inlet manifold (not shown) of the engine.

The exhaust gases admitted to chamber 7 pass out through opening 15 in the end of the exhaust manifold 5 (see Fig. 4) and, between the said opening 15 and the exhaust from the end cylinder of the engine, another outlet 16 is provided which outlet is controlled by valve 17. The spindle of said valve 17 extends through the exhaust manifold (see Fig. 1) and has attached thereto an arm 18 to which is pivotally attached a screw threaded rod 19 the position of the pivotal connection of the latter being adjustable by nut 20.

To prevent any vibration of the rod 19 a spring 21 may be coiled about same between the sleeve 22 and stop nut 23.

The rod 19 is employed to control the valve 17 and this may be effected thermostatically by a flat spiral spring 24 of two metals having different coefficients of expansion housed within a chamber 25 on the wall of the manifold chamber 7 (see Figs. 3 and 4). The spring 24 is substantially wide and more or less rigid transversely to prevent buckling under heat in-

- fluence. The spring 24 has its inner end attached to an axial pin 26 which extends through said chamber 25 and has a terminal disc 27 for increasing or decreasing, by 5 winding or unwinding, the tension of the spring. The disc 27 is retained in set position by one or more pins 28 passing through apertures provided in the disc and which apertures register with similar apertures in 10 the wall of said chamber 25. The outer end of said spring 24 is connected to a pin 29 the outer end of which latter operates in a slot 30 in an arm 31 loosely hung from pin 26.
- 15 The end of the rod 19 is pivotally attached to the outer end of said arm 31.
- Under working conditions the whole of the heated exhaust gases pass from manifold 5 through chamber 7 thence away 20 through outlet 15 and when the heat so applied to the retort 8 exceeds a predetermined degree the spring 24 operates by unwinding to draw upon the arm 31, rod 19, and arm 18 to open valve 17 and allow some 25 of the exhaust gases to by-pass through opening 16 until such time as the chamber 25 has become cooler when the return movement of the spring 24 will operate to close said valve 17.
- 30 I claim--
1. In an internal combustion engine, an exhaust manifold having an enlarged portion

at its discharge end adjacent one of the engine exhaust ports and having an outlet in said enlarged portion, a conductor for 35 conducting carburetted mixture between a carburetor and an engine in-take manifold, a retort having a single opening detachably connected to and extending into said enlarged portion, said retort having substantially lateral communication with said conductor, and said conductor having an internal, substantially transverse groove entering the mouth of said retort, and a by-pass valve for said manifold. 40

2. In an internal combustion engine, an exhaust manifold having an enlarged end portion adjacent an engine cylinder exhaust and having a discharge opening therein, a by-pass opening in said manifold adjacent 50 said enlarged portion, a valve therein, a chamber on said enlarged portion, a spirally wound bi-metallic thermostatic strip in said chamber, means to adjust said strip, an adjustable connection between the strip and 55 valve, a retort detachably connected to and entering said enlarged portion, and a conductor with which said retort laterally communicates, said conductor having an internal groove entering into the mouth of said 60 retort.

Dated this 11th day of July 1923.

G. HAMILTON-GRAPES.
